ATTORNEYS

UNITED STATES PATENT OFFICE.

LOUIS B. PRAHAR, OF NEW YORK, N. Y.

FRAME FOR BAGS, PURSES, SATCHELS, &c.

SPECIFICATION forming part of Letters Patent No. 655,512, dated August 7, 1900.

Application filed June 14, 1900. Serial No. 20,266. (No model.)

To all whom it may concern:

Be it known that I, LOUIS B. PRAHAR, a citizen of the United States, and a resident of the city of New York, borough of Brooklyn, in the county of Kings and State of New York, have invented a new and useful Improvement in Frames for Bags, Purses, Satchels, and the Like, of which the following is a full, clear, and exact description.

10 The purpose of the invention is to provide a locking device for single or double frames for bags, purses, satchels, and the like of such construction that a catch-button will have rocking and guided movement on a member of the frame and may be released from a locking stud or studs on any number of members of the frame by simply rocking the button to one side or the other or by drawing the button upward.

Another feature of the invention is to simplify the construction of such locking devices and render them more adaptable to a frame than heretofore and to provide for a rotary action of the catch-button upon its support without interfering with the locking properties of said button.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

35 Figure 1 is a side elevation of a chatelaine bag, illustrating the improvement in frames applied thereto. Fig. 2 is a partial plan view of a single frame, illustrating the application of the improvement to the frame, the view 40 being drawn on an enlarged scale. Fig. 3 is a view similar to Fig. 2, the improvement being applied to the frame in a slightly-different manner. Fig. 4 is a central transverse section through the frame and its improved locking device, the members of the frame being closed. Fig. 5 is a view similar to Fig. 4, the members of the frame being open; and Fig. 45 6 is a central transverse section through a double frame and the locking device adapted 50 to such a construction of frame.

In the single form of frame two jaws A and

B are employed, suitably pivoted together, and the jaw A is provided with an inwardly-extending flange 10 at the top, and the jaw B is provided with a similar flange 11. When the jaws are closed, the two flanges 10 and 11 are usually brought together, as shown in Fig. 4. The flange 11 of the jaw B is provided at its center with a stud 12, the outer vertical edge of which is preferably straight and the inner vertical edge inclined, as illustrated in Fig. 5. The locking device is applied either in the form of a plate 13, secured to the flange of the frame A by rivets 14 or their equivalents, said plate extending over the flange of the opposing jaw, or instead of the plate 13 a longitudinal lip 15 may be formed integral with the inner edge of the flange of the jaw A, as shown in Fig. 3, in which event the flange of the opposing jaw B will pass beneath this lip. 55 60 65 70

At the central portion of the plate 13 a conical bearing 15^a is formed, usually by striking up the metal of the plate 13; but when the improvement is applied, as shown in Fig. 3, 75 this conical bearing is formed from the metal of the flange 10 and that of the lip 15. At the front of the conical bearing 15^a or that portion of the bearing which faces the stud 12 a vertical slot 16 is made in the bottom of the 80 conical bearing and into the edge of the plate 13 or the lip 15 at such point. This slot 16 is adapted to receive the stud 12 of the jaw B when the two jaws A and B are brought together. A catch-button 17 is used in connection with the conical bearing 15^a, and this button, which may be of any desired exterior shape, is provided with an interior chamber 18, open at the bottom, and said chamber 18 is of such formation that it will loosely receive the conical bearing 15^a and enable the catch-button to rock and turn on the bearing. 85 90

A pin 19 is secured in any suitable manner in the upper central portion of the catch-button 17. Usually the pin is held in place by frictional contact. This pin extends into the chamber 18 of the catch-button and is passed through an elongated slot 20, made in the top of the conical bearing 15^a. A head 21 is formed at the lower end of the pin within the conical bearing 15^a, and a spring 22 is coiled around the pin within the said bear- 95 100

ing, resting upon the head 21 and against the upper portion of the bearing, as is shown in Figs. 4 and 5. When the jaws are together, as shown in Fig. 4, and the catch-button is in its normal position, a wall of the chamber 18 will engage with the outer longitudinal edge of the stud 12 of the jaw B and will hold the jaws closed. When it is desired to open the frame, the catch-button is rocked in a direction opposite to the location of the stud 12, freeing said stud, as shown in Fig. 5, and when the catch-button is released it will resume its normal position. When the frame is to be again closed, the two jaws are simply pressed together, whereupon the inclined face of the stud 12 will force the button back until the stud reaches a point within the chamber 18 of the button. The conical bearing 15^a serves as a guide for the catch-button, and it is evident that the button may be freely turned around the bearing without in the least interfering with the locking engagement of the button with the frame.

In Fig. 6 I have illustrated a double frame comprising jaws A and B and a main or body strip C, which extends over the flanges of the two jaws. Under this arrangement the improvement is applied to the body-strip C, and each jaw is provided with a stud 12^a, and each stud enters a slot 16^a, made in opposite sides of the conical bearing 15^a. Otherwise the construction of the device is the same as that applied to the single frame; but it will be understood that the catch-button may be rocked either to the right or to the left for releasing and locking purposes in this form of the device, whereas in the single form of frame while the catch-button is likewise free to be rocked to the right or to the

left it is in locking engagement with the stud 40 at one side only.

Having thus described my invention, I claim as new and desire to secure by Letters Patent—

1. The combination, with the members of a frame, and a stud carried by one of said members, of a conical extension formed upon the opposing member of the frame, said extension having an opening to receive said stud, and a spring-controlled catch-button for the stud, mounted to turn and rock around and upon the said bearing, for the purpose described.

2. The combination, with the members of a frame, one of said members being provided with a stud having an inclined inner longitudinal surface, of a conical bearing located upon the opposing member of the frame, which bearing is hollow and provided with an upper elongated slot and a slot at its base adapted to receive said stud, a chambered catch-button mounted to turn and to rock upon the conical bearing, a pin connected with said button, which pin is passed through the elongated slot in the conical bearing, terminating in an enlargement at its inner end, which end is within the conical bearing, and a spring likewise located within the conical bearing, which spring is coiled around said pin, for the purpose set forth.

In testimony whereof I have signed my name to this specification in the presence of two subscribing witnesses.

LOUIS B. PRAHAR.
